The ornamental design for an optical connector housing as shown and described.

DESCRIPTION

FIG. 1 is a front, top and right-side perspective view of an optical connector housing showing my new design; FIG. 2 is a rear, bottom and left-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.
